UNITED STATES PATENT OFFICE.

CLAUDE SMITH, OF CHICAGO, ILLINOIS.

CONTINUOUSLY-OPERATED KILN.

Application filed February 23, 1923. Serial No. 620,574.

To all whom it may concern:

Be it known that I, CLAUDE SMITH, a citizen of the United States, residing at Chicago, in the county of Cook and State of Illinois, have invented certain new and useful Improvements in Continuously-Operated Kilns, of which the following is a specification.

Prior to my invention it has been customary to burn clay products such as brick, tile, etc., either in kilns in which the products are deposited or stacked in stationary charges and which therefore require intermittent operation, the products being removed and replaced between successive firings, or in continuously operated kilns in which the brick or the like are fed through long horizontal tunnels or kilns and submitted therein to the flames and products of combustion necessary to dry, heat and bake them at the required temperature. The objections to the first named style of kiln are many and obvious. Among the objections to the horizontal form of kiln may be mentioned the fact that it is impossible in such a kiln to get uniformity of treatment. The hot gases and products of combustion by which the kiln is heated, naturally seek the upper portion of the kiln and the lower portion thereof is therefore much cooler, the articles treated therein being in consequence imperfectly burned; or, if heat is maintained sufficient to properly burn the lower part of the charge, it is unnecessarily high in the upper portion or vault of the tunnel. The operation of such continuous kilns is therefore inefficient and wasteful. Furthermore, because of the difficulty of thoroughly baking the lower layers, due to the uneven heat distribution, the process is necessarily slow and on this account expensive.

In the kiln which forms the subject matter of this application, the clay products treated, which may be brick, tile or other clay wares, are successively dried, burned and cooled in vertical shafts having the advantage among others over the horizontal shafts that the hot air, gases and products of combustion naturally distribute themselves substantially uniformly throughout the cross-section of the shafts so that all the articles undergoing treatment at any particular level at any particular time are under substantially the same conditions of temperature, etc. In the preferred form of the invention the kiln is constructed in two shafts connected by a

flue at their tops, and the fire boxes or other means for providing the hot air and gases for burning and drying the brick are connected to one of said shafts midway the top and bottom thereof so that the gases, etc., rise to the top of said shaft and then are conveyed across and down the other shaft. The brick or other wares treated are conveyed against the current of gases, first upwardly through the last mentioned shaft to the top thereof, then transferred by suitable transfer mechanism to the first mentioned shaft down which they are slowly conveyed, their temperature being gradually raised from the time they enter the last mentioned shaft until they reach the fire boxes on their passage down the first mentioned shaft, after which they are gradually cooled and finally removed at the bottom thereof. The brick are thus gradually heated, dried and burned and then cooled before their removal from the kiln, and the air entering the kiln is gradually heated by the descending brick as it ascends to the fireplaces after which, mingled with the products of combustion, it is gradually cooled until substantially all the heat is extracted by the articles being treated. The construction is therefore not only efficient in that it treats all the material equally and in precisely the same manner, but is economical in that all of the heat furnished by the fireplaces substantially is utilized.

In the accompanying drawings I have shown and in the following specification described a preferred form of my invention. It is to be understood, however, that the specific disclosure is for the purpose of exemplification only and that the scope of the invention is defined in the following claims in which I have endeavored to distinguish it from the prior art, so far as known to me, without however relinquishing or abandoning any portion or feature thereof.

Referring to the drawings Fig. 1 is a vertical section representing a building in which a kiln of my improved construction is erected; Fig. 2 is a vertical section on a plane parallel to that of Fig. 1, showing the kiln on an enlarged scale; Fig. 3 is a vertical section of the shaft in which the wares receive their final treatment on the plane of line 3—3 of Fig. 2; Fig. 4 is a similar view of the other shaft; Fig. 5 is a horizontal section on an enlarged scale of the burning shaft on the line 5—5 of Fig. 2; Fig. 6 a

- similar section of the drying kiln on the line 6—6 of Fig. 2; Fig. 7 a horizontal section through the kiln on the plane of the line 7—7 of Fig. 2; Fig. 8 a side elevation of a unit stack of brick as it is removed from the drying to the burning shaft; Fig. 9 a plan of a pallet used in the handling of the brick; Fig. 10 a side elevation of the carrier forming a part of the transfer mechanism; Fig. 11 an end view of the same; Fig. 12 a detail in elevation; Fig. 13 a side elevation of a modified form of the kiln on a reduced scale; Fig. 14 a vertical section on the plane of the lines 14—14 of Fig. 13; and Fig. 15 is a side view partly in elevation of a detail.

Each part or element of the construction is identified with the same reference character wherever it occurs throughout the several views.

- 20 Referring first to Fig. 1, I have shown the kiln as comprising the drying shaft A and the burning shaft B enclosed in the building C, which serves as a support for the transfer mechanism indicated generally 25 at D. The brick stacked ready for conveyance into the kiln are shown at E with tracks F leading therefrom to the kiln for conveying the brick to the latter. Similarly at G are shown tracks for conveying away the brick or other material after having been treated.

In the form of the invention shown in Figs. 2 to 7 inclusive, the vertical shafts A, B, are connected at or near their upper ends by a flue 10, the shaft B being provided at a point preferably more than half way up with the heating means which are illustrated as fire boxes 11, 11 (see Fig. 3). Preferably the shafts are composed of steel jackets 12, 13, suitably reinforced by longitudinally extended beams 14, 16, and lined with brick as at 17, 18. The lower end of shaft A is connected by a flue 19 (Fig. 7) with a fan chamber, chimney, or other suitable suction device H. The shaft B is provided at its upper end with a side door 20, and a cover door 21, and shaft A with a similar side door 22 and cover 23, which doors and covers are normally closed. More or less air is permitted to enter the bottom of the shaft B, as for example through the doorway or opening 24 (see Fig. 2) and, being drawn upward in said shaft, mixes with the hot gases issuing from the fire boxes 11, flows upward through shaft B, across through flue 10 to shaft A and thence downward to flue 19. As will hereafter appear, the shafts are kept practically or completely filled with brick or other earthen ware to be dried or fired, which earthen ware is continuously introduced to the bottom of the shaft A, conveyed upward slowly and intermittently therein, transferred to shaft B and slowly lowered therein to be removed through the opening 24. Thus the brick is first intro-

duced to the gases and products of combustion from which the heat has been largely extracted, and as it rises through the shaft A is gradually heated and dried by coming into contact with increasingly heated products of combustion, is transferred to the top of shaft B, fed downwardly therein reaching the zone of maximum heat at about the fire boxes, at which point the burning is completed, and then gradually cooled by being lowered through the incoming air in the bottom of the shaft B, which it serves to pre-heat before the air reaches the fire boxes.

In the construction shown diagrammatically in Figs. 13 and 14, the circulation of gases and products of combustion is slightly modified, the construction being otherwise the same. In this form of the device a cross-flue 25 connects the lower portion of the shaft B at 26 with approximately the central portion of shaft A at 27 whereby a portion of the preheated air from the former is carried directly into the latter shaft to assist in the drying of the brick therein. The shaft A is also provided with circulating flues 28, 29 connected to said shaft at their bottoms by openings 30, 31 and at their tops by openings 32, 33, fans 34, 35, or other circulating devices being installed intermediate said upper and lower openings to force the circulation from said lower openings through the circulation flues and back into the shaft through the upper openings. In Figs. 13, 14, I have also shown a bustle pipe 36 surrounding the upper end of shaft A and connected to the cross-flue 10' for distributing the gases therefrom more evenly through the shaft A.

The mechanical means for handling or carrying the brick are the same which ever circulation of air and gases is employed. Broadly speaking, they comprise endless chain means for supporting slowly and intermittently elevating brick in the shaft A and for slowly and intermittently lowering it in the shaft B, the operating mechanism for the chains being so connected that the weight of brick in one shaft is substantially balanced by the weight of the brick in the other shaft whereby comparatively little power is required to effect the necessary slow movement of the chains.

Specifically, the brick handling means in the two shafts differ for a reason which will appear. In each shaft an opening is formed in the lower end thereof, the opening 37 in the shaft A being for the introduction of the brick, and the opening 24, referred to above, in the shaft B being for the removal of the brick. These openings may be closed in any suitable manner except during the insertion or removal of the brick. Referring now to Figs. 2, 4 and 6, it will be seen that the means for traversing the bricks upward

through the shaft A consists in two series of chains 40 arranged respectively upon the opposite side walls of the shaft. Each series, in the particular construction shown, 5 comprises four chains extending nearly the length of the shaft, carried at their upper ends by driven sprockets 41, and at their lower ends by idler sprockets 42. As shown in Fig. 4 the sprockets are mounted in slots 10 or apertures extending through the wall of the shaft so that the chains move upward within the shaft, and downward outside the shaft. Within the shaft the chains run in channels 43 formed by embedding channel 15 irons within the brick work (see Fig. 6). The shaft is braced on the exterior by vertical I-beams 44 of which there is one directly opposite or in register with each channel, and the beams are provided at their 20 upper ends with brackets 45 in which the shafts 46 carrying the driven sprockets are journaled. The idler sprockets 42 are mounted on shafts 48 which are journaled in pillow blocks 49 secured to the concrete 25 or other base of the shaft (see Fig. 12). The means for driving the sprockets 41 will be described later.

At regular intervals each of the chains is provided with rests, chairs or supports 50, 30 each of which supports is so secured to a link as to be maintained in the position shown in Fig. 4 with reference thereto. The chains on both sides of the shaft are so mounted and adjusted relative to each 35 other that for each chair on any chain there is a corresponding chair on each of the other chains. Thus as the chains move upward within the shaft A successive horizontal series of chairs are presented, each series 40 comprising four chairs, or eight in all.

For the purpose of presenting the brick to be supported by the chains and carried upwardly through the shaft A, they are stacked in uniform stacks or units, each 45 stack being carried by a pallet 51. The construction of these pallets is best seen in Fig. 9. It comprises a pair of parallel side-bars 52, 52 which may be conveniently formed of pipe of suitable strength, and 50 cross-bars 53 connecting the same which may properly be formed of small channel beams. The pipes and channel beams are rigidly connected together. The cross-bars 55 are of such length and the longitudinal bars consequently so spaced that when the pallet is placed in the bottom of the shaft A in horizontal position, the longitudinal bars are in the path of movement of the respective series of chairs and adapted to be 60 picked up thereby. For convenience of handling, the loaded pallets are stacked upon supports 54 adjacent tracks 55 upon which a truck 56 is adapted to travel. The roof 57 protects the brick on the supports 54 65 from the weather. The tracks 55 extend

into the lower end of the shaft A (see Fig. 7) so that successive pallets carrying stacks of brick, may be transferred by hand or otherwise to the track and carried into the lower end of the shaft A. Each brick-carrying pallet is placed on the truck in such a position that when the latter is shoved into the bottom of shaft A the longitudinal bars 52 of the pallet extend close to the chains on their respective sides of the shaft 70 and in position to be engaged by the chairs on said chains as previously described. Preferably I provide a pair of stands 54^a upon opposite sides of the tracks 55 which stands are adapted to receive the pallets of 75 brick conveyed into the shaft from the truck, thus releasing the latter for further service. For this purpose the top or platform 56 of the truck is made adjustable vertically and the stands are of a height intermediate the height of the platform when in its upper and lower positions respectively. The truck is run into the shaft with the platform raised slightly higher than the stands and when the proper position is 80 reached the platform is lowered, thus transferring the pallet with the brick thereon to the stands and freeing the truck. In Fig. 15 I have shown a suitable construction of 85 truck for the above purpose. The truck 90 comprises a stationary frame 58 carried by the wheels 59 and provided with guides 62 which receive and guide the slides 61 arranged on opposite sides of the adjustable platform 62^a. The latter comprises end 95 pieces 60 and side members 62^b. The slide 61 and guide 62 maintain the horizontal position of the adjustable platform but the latter is supported from the stationary frame of the truck by means of rollers 66 100 carried on arms 65 attached to shafts 63 journaled in standards 64 on said frame. Shafts 63 also carry worm sectors 67 which are engaged by worms 68 upon a longitudinal shaft 69 provided with handles 70 for 105 turning the same. Obviously, by rotating the handles 70 and shaft 69 the platform may be adjusted and fixed in adjusted position. By this construction or some equivalent means the brick may be carried into 110 the stack A and deposited on the stands 54^a ready to be taken up by the chains in their upward movement.

The successive pallets each bearing its 115 stack of brick are picked up from the stands and slowly lifted through the drying shaft A, arriving successively at the top thereof. As each unit reaches the position shown at a in Fig. 4 the doors 22, 23 are opened to permit the engagement of the brick by the 120 transferring mechanism by which the brick is carried to and deposited in the burning kiln or shaft B. The precise character of this transfer mechanism is not material to 125 this invention in its broader aspect. In the 130

specific form of the invention illustrated the transfer mechanism is adapted to permit the brick to be transferred to the burning shaft without the pallets the brick being stacked in a continuous column in said shaft. Referring more particularly to Figs. 8 to 11 inclusive, it will be observed that the transfer mechanism comprises a carrier 71 having a series of supporting bars or tines 72 which are so spaced as to enter between the cross bars or slats 53 of the pallets. The tines are not directly connected together but each is supported towards its rear end by an upright 73 and braced to maintain its angular position with respect to said upright by a strut 74 extending from its rear end 75 and secured to the upper end of its upright 73. The end tines are preferably inverted U-shaped in cross section, as shown at 76 and are connected by struts 77 with upper horizontal bars 78, the rear ends of which are likewise connected to the upper ends of the uprights 73. Each end of the carrier is therefore in the form of a trapezoidal frame braced by an upright. The two end frames are connected together by the transverse members 82 at the upper ends of the uprights, the transverse members 83 and 84 connecting the forward upper corners of the end frames and the transverse L-bar 85 connecting the uprights towards their lower ends. Said end frames are further secured together by the round bars 86, 87, 88 extending between them at their upper rear corners, at an intermediate point on the upright members and at their forward upper corners respectively. Nuts 89, 90, 91 screwed on the respective ends of the several rods outside the end frames prevent the latter spreading. The intermediate tines at their forward ends consist of a T-bar 79 which is supported by member 80 secured to the web 81 of the T-bar beneath the top thereof and to an upright 73' as well as a flat strut 74 extending from the rear end of said tines to the upper end of an upright 73'. For each tine also and connected to the upright and rear brace or strut thereof, there is a parallel upper bar 78 but no forward brace or strut corresponding to the struts 77. The round rod 87 extends through each of the uprights of the several tines, and similarly the rod 76 extends through the rear ends of the upper bars 78 and the upper end of the rear strut of each tine and the bar 88 extends through the front end of each upper bar. Between the uprights on the bar 87 are arranged spacing sleeves 92 for holding the uprights in their spaced relation and similar sleeves for similar purposes are provided on the rods 86 and 88. There is thus secured a rigid carrier, the tines of which are adapted to extend between the slats of the pallets and engage with their broad upper surfaces the bricks supported

thereby. As shown for example in Fig. 8, the upper two courses of brick, (or in case tile is being treated the arrangement is substantially the same,) are so grouped as to afford spaces for the tines of the carrier to 70 enter between them to engage the unit or block of brick immediately above. The broad supporting surfaces of the tines are of such length as to completely underlie the stack of bricks when the carrier is in position to raise a unit, but are so short as to just clear one of the longitudinal bars of the pallet when the other longitudinal bar lies between the uprights 73' and the rear ends 93 of the supporting surfaces. When the 80 carrier, therefore, is raised by the means hereinafter described the supporting surfaces or other tines engage and support the brick or other material on the pallet and also one of the longitudinal bars of the latter, but the pallet being engaged at no other point swings downward away from the brick to a vertical position or it may be swung back of the carrier out of the way as desired, and when the load of brick has been deposited in the manner hereinafter described the pallet may be removed from the carrier for further use and the carrier is then in condition to receive another load of brick. As the uppermost pair of layers of brick of 95 each unit are formed into spaced columns or supports adapted to receive between them the tines of the carrier, and as each unit is conveyed in this condition into the burning kiln, the following unit or block may be deposited thereon by running the carrier into the upper end of the burning kiln with the tines thereof between such columns, lowering the carrier until the brick thereon rest on the columns of the unit below and then 100 withdrawing the carrier.

Any suitable means may be employed for moving the carrier from its position within the one shaft to its position within the other shaft and I have shown in Fig. 1 a well-known mechanism of this character, the details of which are so familiar that they need not be discussed. The building C containing the kiln is provided with tracks 94, 94 on its opposite side walls, upon which a traveling frame 95 is supported by rollers 96 in the usual manner. Said frame is formed or provided with tracks 97 upon which a trolley 98 may be reciprocated, which trolley directly supports the carrier heretofore described. It is necessary to provide means for raising and lowering the carrier with reference to the trolley, which may be accomplished in a variety of well-known ways as, for example, by suspending the carrier by cables 99 secured to a windlass 100 upon which the cables may be wound. The windlass is provided with a ratchet and pawl for preventing unwinding to maintain the carrier at any altitude to which it is wound. 120

Referring now more particularly to Figs. 2, 3 and 5, it will be seen that the burning kiln or shaft B, as above stated, is provided, below the fire boxes, with endless chains 103 of less length than the similar chains in the other shaft, but similarly mounted in the walls of the shaft. Vertical beams 104 support the brackets 105, furnishing bearings for shaft 106^a of sprockets 106 and sprockets 107 at the lower ends of said beams are mounted in a manner similar to sprockets 42 in shaft A. The chains 103 are also provided with chairs 108 which may be in all respects similar to the chairs 50 in stack A and serve to support the column of brick. In shaft B, however, the brick are supported above the chains in a continuous column and without the use of pallets. For this purpose bars 117 are supported upon the chairs 108 and in turn support the beams 118. It will be recalled that the upper pair of layers of brick of each unit are arranged in spaced columns which serve, as previously described, for the entry of the tines of the transferring device between them and this arrangement is maintained in the column of brick in the burning kiln as it descends to the chains. The transverse spaces between the columns have the further purpose and function to permit the insertion of the bars 118 which takes the weight of the column of brick above them. The method of inserting the bars 117 and 118 will be understood from the following. We have referred to the tracks 112 within the lower end of a shaft B for permitting the entry thereto of the truck 121 by which the brick are removed from the shaft and on opposite sides of the tracks are stands 54^b in the bottom of shaft A. These stands are adapted to receive the lowermost set of beams 118 and temporarily relieve the chains of the weight of the column of brick when the chains are lowered for this purpose. As each succeeding unit of brick at the lower end of the column is ready for removal, it is lowered until its supporting beams 118 rest upon said stands. The chains are then given a further movement in the same direction sufficient to permit the placing of the bars 117 and the beams 118 under the second unit above the unit which is to be removed. By reference to Fig. 5 it will be seen that one of the end walls of the shaft B is formed with openings 120 through which the bars 117 may be inserted and placed upon the chairs 108 and the side walls of said shaft are formed with openings 119 through which the beams 118 may be placed in position between the spaced columns of brick constituting the upper layers of the unit next above that to be removed. When these bars and beams have been placed in position the chains are moved to a slight extent in the opposite direction so that the newly inserted bars and beams 65 take the load of the column of brick, relieving the bottom unit which is now resting on the stands 54^b. The lower unit is now removed from the stands by raising the adjustable platform of the truck 121 which, as shown in Fig. 2 is provided with I-beams 123 so spaced apart as to receive between them the beams 118 supporting the lower unit. As the platform of truck 121 is raised, therefore, the I-beams 123 take the weight 75 of the unit of brick, releasing the beams 118 which are received upon the platform between beams 123. The truck is now withdrawn from the shaft B with the unit of brick upon it and may be discharged by any 80 suitable means of its load of brick and beams and returned to the shaft B for another load. The beams 118 which are removed are of course available for reuse in shaft B. After the weight of the column of bricks has been 85 removed from the lowermost unit by reversing the movement of the chains, the weight of said column is shared between the two sets of beams 118 which are then in place 90 on the chains. After the burning and cooling have prepared another unit for removal it is lowered on to the stands and removed by a repetition of the operations just described. In order to facilitate the insertion of bars 117 and beams 118 a platform 124 95 surrounds shaft B at a suitable elevation.

It remains to describe the means for operating the chains. For this purpose the sprockets 41 in shaft A are fast upon their shafts 46 and the latter are extended beyond 100 shaft A toward shaft B and provided with bevel pinions 125 which mesh with pinions 126 upon upright shafts 127 which carry at their lower ends pinions 128 by which said shafts are driven (see Figs. 2 and 7). The 105 pinions 128 are driven by bevel pinions 129 on the ends of shafts 130 which carry the worm wheels 131. Said worm wheels are driven by worms 132 on horizontal shaft 133. The worms 132 also engage and drive the worm wheels 110 upon the shafts of 110 which are mounted beveled pinions 134 which drive pinions 135 upon the lower ends of shafts 136. The latter drive the shafts 106^a by means of bevel pinions 137 (see Fig. 2). The shaft 133 is driven from a motor 116 through the medium of a belt 138 and gears 113, 114. It will now be seen that the columns of brick in the two shafts substantially balance each other, and the motor is substantially relieved of strain except such as is necessary to overcome the friction of the parts.

I claim:

1. In a kiln for burning and drying brick, etc., a vertical drying shaft and a vertical burning shaft, means for conveying material up the drying shaft, a firebox commu-

nicating with the burning shaft and a flue connecting the shafts near their respective tops.

2. In a kiln for burning and drying brick, etc., a vertical drying shaft, a vertical burning shaft, a flue connecting such shafts near the tops thereof, means for supplying hot gases to the burning shaft, an exhaust means connected to the bottom of the drying shaft and means for conveying the material up the drying shaft and down the burning shaft.

3. In a kiln for burning and drying brick, etc., a vertical drying shaft and a vertical burning shaft, a flue connecting such shafts near their tops, fire boxes arranged intermediate the upper and lower ends of the burning shaft, an exhaust means connected to the lower end of the drying shaft and means for raising articles to be burned through the drying shaft and lowering them through the burning shaft.

4. In a kiln for drying and burning brick and the like, a burning shaft and a drying shaft, endless chains for raising the brick in the drying shaft, supports at intervals on said chains for supporting the weight of the brick above them, and means for lowering the brick through the burning shaft.

5. In a kiln for drying and burning brick and the like a burning shaft and a drying shaft, a flue connecting shafts near the tops thereof, means for supplying heated gases to the burning shaft and for removing them from the bottom of the drying shaft, means for raising brick in the drying shaft, means for transferring the brick in the drying shaft to the burning shaft and means for lowering the brick in the burning shaft.

6. In a kiln for drying and burning brick and the like, a vertical shaft, sets of endless chains on opposite walls thereof, means for moving said chains upwardly within the shaft, supports on said chains and pallets adapted to receive loads of material to be dried thereon and to be engaged and carried by the supports on said chains, and means outside said shaft for lowering the brick.

7. In a kiln for drying and burning brick and the like, a vertical shaft, series of chains on opposite sides of said shaft, sprockets for said chains so journaled with reference to the walls of the shaft that the chains may move in one direction within the shaft and in the reverse direction outside the shaft, supports on said chains, means adapted to be carried by said supports and to receive loads of brick and means outside said shaft for lowering the brick.

8. In a kiln for drying and burning brick and the like, a vertical shaft, means for supplying heated gases at the top thereof and withdrawing them from the bottom thereof, series of endless chains arranged on opposite walls of said shaft, means for sup-

porting and moving said chains to cause them to move upward within the shaft, supports on the chains and means engaging said supports for carrying loads of material to be treated, and means outside said shaft for lowering the brick.

9. In a kiln for drying and burning brick and the like, a vertical shaft, vertical beams on opposite sides thereof, sprockets mounted at the opposite ends of said beams with in slots in the walls of the shaft, endless chains carried by said sprockets, means for rotating certain of said sprockets to move the endless chains, channels within the shaft in which the inner runs of said chains move, supports on said chains and devices carried by said supports for receiving material to be treated and means outside said shaft for lowering the brick.

10. In a kiln for drying and burning brick and the like, a pair of vertical shafts, means for heating said shafts, means for carrying the material to be treated upward in one of said shafts, means for lowering material to be treated through the other said shaft, a firebox communicating with the latter, and a flue connecting said shafts near their tops.

11. In a kiln for drying and burning brick and the like, a pair of vertical shafts, means for carrying material to be treated upward in one of said shafts, means for lowering material to be treated through the other said shaft, a fire-box communicating with the latter and a flue connecting said shafts near their tops, movable closures for the upper ends of said shafts and means for transferring material being treated from one shaft to the other at their upper ends.

12. In a kiln for drying and burning brick and the like, a vertical shaft, means for heating said shaft, a truck arranged to enter the lower end of said shaft, a series of pallets to be carried by said truck, endless chains on opposite sides of said shaft having at intervals thereon means adapted to engage said pallets on the truck and raise them from the truck, and means for removing said pallets from the upper end of the shaft.

13. In a kiln for drying and burning brick and the like, a vertical shaft having an opening in the lower end and a second opening in the upper end thereof, means for heating the said shaft, a truck having a vertically movable platform thereon adapted to enter the lower end of said shaft, a series of pallets adapted to support brick and to be carried by said truck into said shaft, series of endless chains on opposite sides of said shaft, means for supporting and moving said chains upwardly within the shaft and chairs on the chains adapted to engage the pallets for raising the same from said truck.

14. In a kiln for drying and burning

- brick and the like, a vertical shaft, means for opening and closing the upper end of said shaft, an opening in the lower end of said shaft, means for supplying heated gases to said shaft, a truck adapted to enter the opening in the lower end of said shaft, endless chains on opposite sides of said shaft having chairs at intervals thereon and pallets adapted to receive articles to be heated and to engage the chairs on the chains and to be raised by the latter from the truck.
15. In a kiln for drying and burning brick and the like, a vertical burning shaft, means for introducing heated gases thereto intermediate its ends, endless chains on opposite walls of said shaft adjacent the lower end thereof, means for supporting material being burned from said chains and means for removing the material from the lower end of said shaft.
16. In a kiln for drying and burning brick and the like, a vertical burning shaft having means for closing the same at the upper end and an opening at the lower end, a truck having a vertically adjustable platform adapted to enter said shaft to receive a load of treated material, means for raising and lowering the platform of the truck, endless chains on opposite sides of said shaft near the lower end thereof, supports on said chains, means for supporting the material being burned from said supports and transferring them to the platform of said truck.
17. In a kiln for drying and burning brick and the like, a vertical burning shaft, means for opening and closing the same at the upper end thereof, said shaft having an opening at the lower end thereof, a truck adapted to enter the lower end of the shaft through said opening, an adjustable platform on said truck, transverse supports 123 on said truck platform, endless chains mounted on opposite walls of said shaft and having supports arranged at intervals thereon, beams received by said supports and sup-
- porting loads of brick, there being openings 119 in the walls of said shaft for the insertion and arrangement of said beams.
18. In a kiln for drying and burning brick and the like, a pair of vertical shafts, series of endless chains on opposite walls of each said shaft, means for heating said shafts, means for supporting materials to be dried and burned from said chains and common means connected to the chains on both shafts for moving the chains in one shaft upward and in the other shaft downward whereby the load in one shaft counterbalances the load in the other shaft.
19. In a kiln for drying and burning brick and the like, a pair of vertical shafts, means for heating said shafts, means for conveying material to be treated from the top of one of said shafts to the top of the other, series of endless chains on the opposite walls of each said shaft, sprockets for supporting and driving said chains, shafting and gears connecting said sprockets in the respective shafts whereby the load in one shaft is substantially counterbalanced by the load on the other shaft, and means for driving said mechanism.
20. In a kiln for drying and burning brick and the like, a pair of vertical shafts, a flue connecting said shafts near their upper ends, a flue for exhausting one of said shafts at its lower end, a means for supplying heated gases to the other said shaft intermediate its ends and a flue connecting said shafts intermediate their ends.
21. In a kiln for drying and burning brick and the like, a pair of vertical shafts, a flue connecting said shafts near their upper ends, a means for exhausting one of said shafts at its lower end, a second flue connecting said shafts intermediate their ends and means for propelling the gases in said second flue.

CLAUDE SMITH.
